DESIGN FOR A GLIDER

Peter V. Armstrong, Warren, Ohio, assignor to
Federal Machine and Welder Company, War-
ren, Ohio, a corporation of Ohio

Application December 13, 1945, Serial No. 124,667

Term of patent 7 years

(Cl. D15—11)

To all whom it may concern:

Be it known that I, Peter V. Armstrong, a citizen of the United States, residing at Warren, in the county of Trumbull and State of Ohio, have invented a new, original, and ornamental Design for Gliders, of which the following is a specification, reference being had to the accompanying drawing, forming part thereof.

In the drawing:

Figure 1 is a perspective view of a glider showing my new design,

Figure 2 is a top plan of the glider, on a smaller scale, and

Figure 3 is an end elevational view of the glider.

The beaded appearance of the side standards terminates at the back thereof, and the rear faces of such standards are plain.

The characteristic features of my design are shown by means of full lines in the drawing.

I claim:

The ornamental design for a glider, substantially as shown and described.

PETER V. ARMSTRONG.
